UNITED STATES PATENT OFFICE.

FRANK M. WADE, OF WAUWATOSA, WISCONSIN, ASSIGNOR TO MILWAUKEE PAPER BOX COMPANY, OF MILWAUKEE, WISCONSIN, A CORPORATION OF WISCONSIN.

PAPER BOX.

1,328,935.

Specification of Letters Patent. Patented Jan. 27, 1920.

Application filed March 14, 1918. Serial No. 222,434.

To all whom it may concern:

Be it known that I, FRANK M. WADE, a citizen of the United States, residing at the National Soldiers' Home, in the town of 5 Wauwatosa, county of Milwaukee, and State of Wisconsin, have invented new and useful Improvements in Paper Boxes, of which the following is a specification.

My invention relates to improvements in 10 paper boxes.

The object of my invention is to provide a form of box having interlocking end portions, and a partially open side portion provided with an interlocking cover flap, all 15 composed of a single sheet or strip of cardboard, cut, creased and folded as herein-after described.

A further object of my invention is to provide a knockdown box having permanently 20 connected top, bottom and side walls, interlocking end walls, and an interlocking cover flap, which may be folded for shipment in the form of a flat set of superposed cardboard strips, and reassembled in box 25 form by a mere swinging adjustment of the side walls, and by folding the end wall members inwardly and interlocking them in assembled relation.

In the drawings:—

30 Figure 1 illustrates my invention as it appears in knockdown form.

Fig. 2 is a view of the same as seen from the opposite side from that illustrated in Fig. 1.

35 Fig. 3 is a fragmentary view, showing the members composing the end wall, when partially adjusted, in assembled relation.

Fig. 4 is a perspective view of the box 40 as it appears when set up ready for use.

Fig. 5 is a cross section.

Like parts are identified by the same reference characters throughout the several views.

A strip of paper, preferably cardboard, is 45 subdivided by transverse crease lines into a cover flap A, side wall A', bottom wall B, side wall B', top wall C, and connecting flap D, folded as best shown in section, in Fig. 5, with the flap D gummed to the inner surface of the wall A, and with the cover flap in position to close the opening E in the top wall C, said flap having its margins contoured to form a set of corner tongues α , adapted to be received in suitable slits α' , formed in the top wall A, near

two of its corners. The slits extend diagonally across the corners of the top wall A in a position to receive the tongues in interlocking relation. Inasmuch as the crease lines form flexible corner joints, it is obvious 60 that the side walls A', B', may be swung in one direction to allow the top wall A to fold downwardly until it rests flat upon a portion of the bottom wall, and upon the side wall B', as shown in Figs. 1 and 2. 65

The end walls are composed of flaps projected from the ends of the top, bottom and side walls, and adapted to be folded to positions in which these members are interlocked with each other at each end of the 70 box. A convenient method of forming these flaps is to provide the top wall A with flaps F at each end, having converging margins F' terminating in an interlocking tongue f. The side walls A' and B' are 75 provided at each end with projecting flaps G, the lower margins of which extend upwardly along curved lines G', continuing along oblique lines converging toward the top margin of the flap, as shown at g, and 80 defining a tongue H adapted, when the flaps are folded inwardly, to be received underneath the top flap F. The bottom wall is provided at each end with a projecting flap I, rectangular in form, and adapted to fill 85 the end of the box when folded inwardly, this flap having upper and lower margins, equal in length to the width of the top wall A and bottom wall B, and its side margins being equal in length to the width of the 90 side walls A' and B'.

The flap I is provided with a transverse slit J, having end extensions K leading upwardly in the wall toward the top of the box, and preferably inwardly curved at L, 95 thereby forming a flexible member M adapted to yield inwardly under pressure.

When the box is assembled in position for use, by swinging the side walls A' and B' to vertical position, the flaps I may be folded 100 upwardly at each end of the box, and the flaps G formed inwardly against the flap I, after which the cover flaps F may be swung downwardly across the tongues H, and the tongue f on the flap F inserted through the 105 slit J, the member M yielding sufficiently to allow the flaps to be thus interlocked without tearing.

The end flaps, when interlocked as above described, will hold the box in position for 110

use, and the box may be opened by releasing the cover flap and lifting it to a raised position, whereupon the contents may be inserted, or subsequently removed, through the opening E in the top wall A.

I attach great importance to the construction above described, for the reason that a box of this kind may be more readily and quickly prepared and packed for shipment, 10 and reassembled at its destination in condition for use than is the case with ordinary paper boxes of the knock-down type. In fact, it is possible to assemble my improved box in substantially the same time that it 15 would require to remove an ordinary box from a shelf, since the top, bottom, side walls and cover flap are permanently connected in an endless series, and merely require to be swung into the form of a rectangular receptacle, and the end flaps adjusted 20 in position to provide a complete receptacle ready for use.

I claim:

1. A knock-down paper box, comprising 25 a set of side, top and bottom walls permanently connected in an endless series, all of said walls being provided with end flaps adapted, when folded, to constitute the end

walls of the box, the bottom flap having a transverse slit and comprising an inner 30 member of the wall, the top flap being provided with a tongue adapted to interlock in said slit, and the other two flaps having their lower margins cut away to allow their extremities to fold upon each other between 35 the interlocking flaps above said slit.

2. A paper box comprising walls connected in an endless series, one of said walls having an extension constituting a cover flap, the adjacent wall having an opening adapted 40 to be normally closed by said cover flap, an end flap upon each wall adapted to constitute an end wall of the box, one of said flaps having a transverse slit and comprising an inner member of the end wall, the opposite flap being provided with a tongue adapted 45 to interlock in said slit, the other two flaps being cut away permitting them to fold upon each other above said slit and between said interlocking flaps.

In testimony whereof I affix my signature in the presence of two witnesses.

FRANK M. WADE.
